UNITED STATES PATENT OFFICE

162,061

STOCKING

Ralph A. Nicoletti, Philadelphia, Pa., assignor to Nu-Clear Hosiery Company, Philadelphia, Pa., a copartnership

Application June 15, 1950, Serial No. 10,530

Term of patent 14 years

(Cl. D47—7)

To all whom it may concern:

Be it known that I, Ralph A. Nicoletti, a citizen of the United States, residing at Philadelphia, in the county of Philadelphia and State of Pennsylvania, have invented a new, original, and ornamental Design for Stocking, of which the following is a specification, reference being had to the accompanying drawing, forming a part hereof.

The figure is a side perspective of a stocking showing my new design.

I claim:

The ornamental design for a stocking, as shown.

RALPH A. NICOLETTI.
